US0D1061763S

(12) **United States Design Patent** (10) **Patent No.:** **US D1,061,763 S**
(45) **Date of Patent:** **** Feb. 11, 2025**

(54) **PUCK**

(71) Applicant: **Tracy Anderson Mind and Body, LLC**, New York, NY (US)

(72) Inventors: **Tracy Anderson**, New York, NY (US); **Paul Dowd**, New York, NY (US); **Josh Goldin**, New York, NY (US)

(73) Assignee: **Tracy Anderson Mind and Body, LLC**, New York, NY (US)

(**) Term: **15 Years**

(21) Appl. No.: **29/882,979**

(22) Filed: **Jan. 20, 2023**

(51) LOC (15) Cl. **21-02**

(52) U.S. Cl. **D21/694**; D21/662; D21/680; D21/686; D21/698

(57) **CLAIM**

The ornamental design for a puck, as shown and described.

DESCRIPTION

FIG. 1 is a front perspective of a puck according to the new design;

FIG. 2 is a front elevational view thereof;

FIG. 3 is a rear elevational view thereof;

FIG. 4 is a right elevational view thereof;

FIG. 5 is a left elevational view thereof;

FIG. 6 is a top plan view thereof; and,

FIG. 7 is a bottom plan view thereof.

The broken lines illustrate portions of the puck and form no part of the claimed design.

1 Claim, 7 Drawing Sheets
